PANEL BOARD UNIT HAVING RENEWABLE FUSES

William H. Frank, Joseph A. Messing, and Harrison J. L. Frank, Detroit, Mich., assignors to Bulldog Electric Products Company, Detroit, Mich., a corporation of West Virginia

Application July 18, 1934, Serial No. 735,744

10 Claims. (Cl. 200—125)

This invention relates to a sectional panel-board made up of units in which branch circuit control switches are combined with fuses forming protective devices, for those circuits.

5 Panelboards of this character are well known in the art. In each known case, however, the fuses of the units are of the conventional plug or cartridge fuse type, requiring replacement of fuses whenever a fuse "blows". In the panel-
10 board of the present invention, the fuses are of the multi-fuse renewable type shown in application Serial No. 666,786, April 19, 1934, which matured into Patent No. 2,000,016, of May 7, 1935; consequently, whenever a fuse "blows", fuse re-
15 newal can be accomplished quickly, easily, and inexpensively, replacement of a multiple fuse wheel not being effected until all the fuses there-
of have been blown, and not until after many fuse renewals.

20 An object of this invention, therefore, is a unit provided with a multiple fuse device and equipped with a circuit-control switch whereby a "blown" fuse can be replaced by a fresh one without disturbing the panelboard arrangements; that is, a new fuse can be put into the circuit to replace the "blown" fuse by a simple operation which can be performed from the front of the panelboard. To attain this result there is constructed a mechanism whereby the above
25 result can be attained through manipulation of the handle of the circuit control switch of the unit. The handle of the circuit control switch, therefore, has a dual function, firstly to control the electrical circuits under normal conditions, and secondly to enable the operator to place a new fuse in the branch circuit when the switch
30 handle is operated.

Another object of the invention is the provision of a switch and fuse unit which can be conveniently opened for replacements and repairs, but only when the switch is in "off" position. When the switch is in "on" position the invention provides an interlock means to lock a cover thereof in unit closing position so that it is impossible to open it and gain access to the fuses therein. When the switch cover can be opened, the parts therein which are exposed are completely segregated from the live parts by the fact that the switch is open, with the result that there is no danger to the operator from electrical shocks, etc.

A further object of the invention is the provision of a switch and renewable fuse device, which
55 allows frequent fuse renewal with the maximum

of convenience, without tampering with the switch parts for the renewal of "blown" fuses.

A further object of the invention is to construct a control switch suitable for cooperating with a multi-fuse wheel of the type shown in our application Serial No. 666,786, April 19, 1934, now Patent No. 2,000,016, of which this application is a continuation in part, so that the latter can be conveniently mounted for replacement, and at the same time devise a mechanism to shift the 10 fuse wheel for fuse renewal.

Further objects of the invention will be apparent from the description and claims following.

An embodiment of the invention will be described in the following specification. The novel 15 features, particularly pointed out in the appended claims, will be illustrated in the accompanying drawings forming a part of the specification. In these drawings,

Figure 1 is a plan view of a double branch 20 single pole panelboard unit, showing the cooperating bus bars in phantom;

Figure 2 is an elevation, showing one of the four covers of the unit in raised position for fuse wheel replacement;

Figure 3 shows a latch detail in section, taken along the line 3—3 of Figure 2;

Figure 4 is a partial section along the line 4—4 of Figure 1, showing the internal construction of a unit of the invention, with the switch in "off" 30 position;

Figure 5 is a similar view, but showing the switch in "on" position;

Figure 6 is an elevation of a cover and fuse wheel assembly, shown with details of the locking 35 spring construction;

Figures 7 and 8 are elevation and plan views, respectively, of the locking-spring shown in Figure 6;

Figures 9 and 10 are sections along line 9—9 40 of Figure 6; Figure 9 shows the switch handle in released position for normal switching operation, and Figure 10 shows the handle in depressed position for changing the position of the fuse wheel for fuse renewal;

Figure 11 is a section along the line 11—11 of Figure 6, showing the locking-spring construction;

Figure 12 is a partial section along the line 12—12 of Figure 4, showing contact and baffle 50 parts of the unit;

Figure 13 is a partial bottom plan view of the unit, showing the bus bars in phantom;

Figure 14 is a section along the line 14—14 of Figure 4;

55

Figure 15 is an enlarged detail of the axle arrangement of the fuse wheel.

The unit

- 5 Referring to Figure 1 of the drawings, there is shown a double branch single pole unit 8 of the invention. The unit shown is in the nature of a cup-shaped body of insulation having a bottom, smooth sides, ends, central parts therein, which 10 divide the unit into two open-top branches, two covers for each branch, hinged to the central parts, and each carrying a switch and fuse wheel assembly. Thus, there are four separate switches, and these control the four separate branch leads. 15 The supply bars 10 are shown in phantom, and the branch leads 11 are shown as leading off from the ends of the unit. The arrangement shown provides for each lead, between a bus bar 10 and the lead, a switching mechanism, and a fuse protective device. In Figure 1, the upper two 20 switches are shown in "on" position, while the lower two are shown in "off" position.

On top of the unit is a supporting plate 13 which is fastened to the central rigid structure 25 therebeneath by means of screws 14. On the side edges of the plate 13 are hinges 15 which mount covers 16, each in turn supporting an assembly of a switch and a fuse wheel 17; the hinges allow the covers to be raised or opened, as shown in 30 Figure 2, so that the fuse wheels 17 are exposed to view, allowing free manual manipulation thereof for fuse wheel replacement, etc., or to be lowered, to close the interior of the unit.

The fuse wheel itself forms the basis of application Serial No. 666,786, which matured into Patent No. 2,000,016, of May 7, 1935, and is there described in detail. For the purposes of this case it is sufficient to say that the fuse wheel may be considered as a flat, centrally apertured disc 35 having on its opposite sides spaced bosses 17' on which lie terminal parts of metal fuses having their fusible portions within the wheel. The terminal parts of the fuses are engaged by stationary contacts of the unit to bridge them and complete 40 the circuits through the units from the bus bars 10 to the branch leads 11. The bosses are circularly spaced and in effect form ratchet teeth for the wheel, to be picked up by pawl-like moving 45 and indexing parts of the switches of the unit, whereby the wheels may be given intermittent 50 rotation for fuse renewal and properly indexed for contact making.

The covers 16 are held in closed position, as shown in Figures 1 and 2, by means of a latch 21, 55 a detail view of which is Figure 3. In general the latch comprises a U shaped spring member 21, held in firm position by a screw. On the upper ends, which pass through apertures 16a in covers 16, nibs 21a are formed, and these engage the 60 upper surfaces of the covers 16 and prevent them from being raised. The ends of the latch 21 may be squeezed together to move nibs 21a and permit the covers to be raised or opened.

There are provided, in the supporting plate 13, 65 windows 22 for observation of indicating legend on a card which may be placed on the rigid structure of the unit, beneath the plate 13.

In the upper surface of each cover 16, a slot 23 is provided through which projects the switch 70 operating handle 24. On one edge of the slot is provided a semi-circular indentation 25, below which is fastened a small plate 26 supported from the cover by means of rivets 27. This plate 26 conforms in contour to the curved surface of the 75 cover, and is provided with an observation hole

28, which pierces the plate 26 at a central position and gives the operator an opportunity to observe the edge 29 of the fuse wheel 17, which edge may be marked with suitable legends, as in Figure 4 of application Serial #666,786.

The slot 23 is of sufficient width to allow the free manipulation of the handle 24 of the switch and is of sufficient length to allow the handle 24 to move to and from "off" and "on" positions.

The switch

5

10

Referring to Figure 4, there is found a cross-sectional view of a switch showing the handle 24 in its "off" position. Supporting plate 13 is here clearly shown attached to the rigid support means 15 32 by means of screws 14, which are threaded into the upper member of the rigid support means 32. On the left side of the plate 13 in this figure is shown the hinge 15, which attaches the cover 16 to the supporting plate 13. Through the elongated slot 23 is projected the lower portion 33 of the handle 24, which is attached to the main portion 34 of the switch lever or bell crank, the latter being pivoted on the axle 35. The axle 35 is journalled in the depending portions 36 of the 20 cover 16 of the switch, allowing movement of the bell crank thereabout from "off" position as shown in Figure 4, to "on" position as shown in Figure 5. On the right side of the main portion 34 of the switch bell crank an ear 40 is found, to which is 25 attached by means of a rivet 41 the connecting link 42 which places the switch lever 34 in operable relation with the switching device whose operating arm is referenced 44. With this arrangement it is 30 obvious that when the switch lever 34 is moved from the position shown in Figure 4 to that shown in Figure 5 it will move the arm 44 in relatively the same distance. This will accomplish the shifting of the depending switch contact arm 45 provided with contact 46 from "off" position as 35 shown in Figure 4 to the "on" position as shown in Figure 5 with a sudden snapping motion. The switching device 44-45 may be of any desired 40 form, as for example of the form shown at Figures 8-9 of application Serial #503,546, now Patent No. 1,974,154, of September 18, 1934, with 45 parts 162-154 thereof corresponding to parts 44-45 hereof, and since the details of this switching mechanism are well-known in the art, they need not be described in detail in this case.

The lower end 47 of the switching lever 34 projects laterally and has at its outer end a lug 48 turned outwardly so as to catch in a hook 49 formed from the rigid supporting base 32. The purpose of this arrangement is to provide an 55 interlocking mechanism for the cover 16. It prevents the opening of the cover to the position shown in Figure 2 when the switch is in "on" position as shown in Figure 5. It is clear that when the projecting lug 48 on the lever 47 is in 60 cooperative engagement with hook 49 as shown in Figure 5, it will be impossible to lift the outer end of the cover 16 so as to open the cover about the hinge 15. However, when the switch is in "off" position, as shown in Figure 4, the lug 48 is clear 65 of the hook 49 so that the opening operation is easily accomplished. This interlocking means gives the operator protection against electrical shocks when he tries to open the cover for repairs, or for replacement of the fuse wheel 17, 70 because the cover cannot be lifted from its position while the switch is in "on" position. It is only when the switch is in "off" position, with all the parts electrically "dead", that the cover can be lifted as described before. In this way there is 75

provided a highly practical means for preventing dangerous shocks, etc., to the operator.

Fusing device

5 Referring now to Figures 9 and 10, the construction of the fuse-changing device will be described in detail.

The switch handle 24 of the switch is of a unique construction, as will now be described. 10 It has an outer cup-shaped portion (Figure 9) with a closed end which is telescoped over an inner tubular portion 54. As shown in Figure 9, a coiled compression spring 55 is positioned between the upper portion of the handle 24 and the 15 lower closed end lug 56 of the tubular portion 54 to push them apart. The spring acts between the inner surface of the cup-shaped upper piece and the lug 56 formed on the inside of the tubular piece 54. The tubular piece 54 is integral with 20 the main switch lever 34 and is attached thereto by means of the lower portion of the handle 33 and the inwardly turned peripheral lug 58. The outer cup-shaped portion of the handle 24 has a narrow downwardly extending strip 64 which 25 extends through a hole 65 in the inwardly turned peripheral lug 58 on the lever 34. The lower end of the downwardly extending strip 64 has an outwardly turned lug 66 which extends through a radial slot 67 in the switch lever 34. The outer 30 end of the lug 66 is in operable engagement with the ramp 69 on the locking spring 70, as clearly shown in Figures 9 and 10. When the upper portion of the handle 24 is pushed downwardly against the action of the spring 55 it will take 35 the position shown in Figure 10. Here is shown clearly how the lug 66 operates upon the ramp 69 of the spring 70, pushing it outwardly as indicated.

It will be noticed in Figure 9 that the lower 40 portion of the strip 64 is capable of being pushed down between the circularly spaced bosses or teeth 17 on the fuse wheel 17. In the present invention, these teeth are used as teeth of a ratchet wheel, to advance the position of the wheel 45 one set of teeth with reference to fixed contact points. In Figure 10 is shown the relation between the teeth on the fuse wheel 17 and the lower portion of the strip 64. It will be seen that if the handle is turned with the upper portion of the handle 24 depressed, strip 64 will fit in between teeth on the fuse wheel 17. Hence, if the handle 24, when it is in depressed position as shown in Figure 10 is given a turning moment, it is clear that the toothed fuse wheel 17 must 50 turn with it. In this way is provided the necessary turning movement to shift the fuse wheel 17 from the position shown in Figure 4, in which the contact strip 85 is in electrical contact with the fuse terminal 75' to the position where the fuse terminal 75'' will be in electrical contact with the strip 85.

As shown in Figure 9, the fuse wheel 17 is journalled on a U shaped axle 35, which is in active engagement with the depending members 55 36 of the cover 16. The details of the axle 35 are clearly shown in Figure 15. It is there seen that the end portions of the U shaped member are bent at right angles to the axis of the axle 35 to form lugs 81. The separate branches of the U shaped axle 35 are fitted into two holes 88 in the right hand depending member 36 of the cover 16, having the strip 89 positioned between the two branches of the axle. The purpose of this is to prevent the axle from becoming detached 70 from the side member 36 and become lost.

To position the fuse wheel 17 on the axle 35 as shown in Figure 9 the operator must remove the pin 90 from the bight of the U shaped axle and then pull the axle as far to the right as possible, so as to place the strip 89 in the extreme 5 lower portion of the bight of the U shaped axle 35. The strip 89 prevents the axle 35 from being removed completely but at the same time gives the operator the opportunity of placing the central hole of the fuse wheel 17 in alignment with the axis 10 of the axle 35 so that it will be a simple matter to push the latter through the central hole of the fuse wheel 17 and to journal the axle in the left hand depending piece 36. When the bight of the axle extends beyond the outer surface of 15 the side member 36, it is a simple matter to slip the pin 90 into position to hold all the parts in operable position.

It will be noticed in Figure 15 that the switch lever 34 has an outwardly extending tubular portion 92 which forms a bearing for the axle 35. At the same time the portion 92 is journalled in the left hand depending piece 36 of the cover 16 so that the switch lever 34 can be operated even though the axle 35 is not in position. Clearly 25 then, even though the fuse wheel is not in position the switch can be operated from and to "off" and "on" positions.

It will also be observed that the tooth which is picked up by the switch handle, for fuse wheel 30 rotation, is not adjacent the tooth which is contacted by contact 85 and therefore energized or live, but is as far from that tooth as is possible, namely diametrically opposite, and this insures safe operation of the handle 24 for fuse renewal. 35

The locking mechanism

Returning to the locking spring 70 with its inclined ramp 69, a locking mechanism will be described which utilizes this spring as its principal 40 operating member. The details of the spring are clearly shown in Figures 7 and 8. Referring to these figures, there is seen a small upwardly extending nib 110 whose function will be described later. On the right end of the spring 70 is an 45 upwardly extending lug 111 which is in active engagement with a tooth of the fuse wheel 17, as is shown in Figure 6, to lock the wheel in position when the switch and fuse wheel are in normal operating position. As shown further in Figure 6 50 the spring 70 is attached to the inner side of the depending side portion 36 by means of two rivets 112. The lower side of the spring 70 is supported from unusual stresses by means of an inwardly 55 extending lug 113 from the side member 36. Further, the spring 70 is supported from unusual upper thrusts by an inwardly extending lug 113a cut from the depending side piece 36, and this lug at the same time acts as a guide for the inclined ramp 69. To prevent the spring 70 from 60 being depressed too far inwardly, there is provided on part 36 an inwardly and downwardly extending lug 114, which also acts as a guide.

As described before, the lug 111 is positioned so as to fit between adjacent teeth of the wheel 65 17 to prevent any rotation of the fuse wheel 17 about its axle 35 when the spring 70 is in normal position. When, however, rotation of the wheel is desired by an operator, he will depress the upper portion of the handle 24 as shown in Figure 70 10, with the result before mentioned; that is, the lug 66 will come into active engagement with the inclined ramp 69 of the spring 70 and tend to push it to the left, as in Figure 10. This action results in a magnified movement on the part of 75

the outer end of the spring 70, and removes the lug 111 out of its place between the teeth of the wheel. At the same time, the lower end of the strip 64 will move into the space between two 5 teeth, as shown in Figure 10; then, any turning moment on the handle will be directly transmitted from the handle 24 to the fuse wheel 17. This will accomplish the result pointed out before; that is, it will shift the fuse wheel about 10 its axis and place into engagement with the contacting strips 85 a new tooth which automatically places a new fuse into the circuit.

In order to prevent the upper portion of the handle 24 from being depressed when the switch 15 is in "on" position, there has been provided the nib 110. When the switch is in the "on" position shown in Figure 5, nib 110 will be in alignment with the axis of the handle 24, with the result that when the handle is depressed at this 20 point the lug 66 will come into contact with the nib. Immediately below the nib is found a supporting lug 113 in the side member 36 which will prevent the spring 70 from being deformed when force is applied to the upper portion of the handle 24. The result will be that the upper portion 25 of the handle 24 cannot be depressed, and hence cannot come into operable relation between teeth on the fuse wheel 17. This arrangement makes the switch inoperable to move the wheel when 30 the switch is on "on" position, and hence prevents the switch from moving the fuse wheel backward.

It will be observed that the lug 111 of the locking spring properly indexes the wheel and insures a whole tooth, and no more or less than 35 that, being in contact with the contact 85. This prevents improper contact between contact 85 and a fuse, as well as preventing contact between contact 85 and more than one fuse.

40 It will also be observed that fuse renewal is accomplished only when the switch is in "off" position, that the action of fuse renewal automatically causes the switch to arrive at "on" position, and that the contact 85 is picked up by a 45 fuse before the switch contact arm 45 arrives at its contact making position, Figure 4, to close the circuit through the fuse engaging contact 85. These characteristics enhance the life of the contacts 85, so necessary to proper circuit protection, by eliminating the possibility of arcing at contact 85, insure good contact to the fuse wheel fuses, and also combine the operations of fuse renewal and circuit closing so that they can be performed with one movement of handle 24.

55 The circuit

Referring to Figure 12, there is shown the electrical connections of the switch. The spring contact 85, which is in electrical contact with 60 the wheel fuses, is attached to the base by means of bolt 120 and pin 121, which extend through the base and the flat portion 85' of the connecting strip. Attached to the bolt 120 which extends through the base 130 is wire 11, which is 65 the lead extending to the controlled circuit. Beginning at this point the circuit is as follows: First, through the contact strip 85 to the fuse terminal 75 on the fuse wheel 17; thence through a fuse incorporated between the terminal 75 and 70 the antipodal terminal 75a; thence to the second contacting strip 85a; thence to contacting strip 85b, which is in operable relation with the switch member 45; thence to a central connecting lug 85c, which is connected to the bus bar strip 140 by means of bolt 141.

Returning to the contact strip 85a, the same is supported by a spring member 142 to give the contacting strip 85a greater resiliency. The spring member 142 is attached to the contact strip by means of rivets 143, it being so arranged that only the outer end of the member 142 exerts its force at the point where the contacting strip 85a makes electrical contact with the terminal 75a.

5 Referring to Figure 12, there are provided 10 proper insulation baffles 156 to give the necessary electrical protection to prevent flashovers, etc.

Now having described the invention and a preferred embodiment thereof, it is to be understood that the said invention is to be limited, not to 15 the specific details herein set forth, but only by the scope of the claims which follow.

What we claim is:

1. A multiple fuse and switch device comprising a movably mounted multiple fuse element, and a 20 handled switch normally disconnected from and movable for normal switching without causing movement of the fuse element, and means optionally operable to create an operative connection between the switch handle and the multiple fuse 25 element whereby the former may be manipulated to effect fuse renewal movement of the latter.

2. A multiple fuse and switch device comprising a movably mounted multiple fuse element, and a 30 handled switch normally disconnected from and movable for normal switching without causing movement of the fuse element, and means optionally operable to create an operative connection between the switch handle and the multiple fuse 35 element whereby the former may be manipulated to effect fuse renewal movement of the latter, the switch and the multiple fuse element being contained within a body closed by a movable cover, the multiple fuse element being movably and removably mounted on the cover so that opening 40 movement of the cover exposes the multiple fuse element for removal.

3. A multiple fuse and switch device comprising a movably mounted multiple fuse element, and a handled switch normally disconnected from 45 and movable for normal switching without causing movement of the fuse element, and means optionally operable to create an operative connection between the switch handle and the multiple fuse 50 element whereby the former may be manipulated to effect fuse renewal movement of the latter, the switch and the multiple fuse element being contained within a body closed by a movable cover, the multiple fuse element being movably and removably mounted on the cover so that opening 55 movement of the cover exposes the multiple fuse element for removal, the cover being interlocked to the switch so as to be openable only when the switch is in off position.

4. A multiple fuse and switch device comprising 60 a movably mounted multiple fuse element, and a handled switch normally disconnected from and movable for normal switching without causing movement of the fuse element, and means optionally operable to create an operative connection 65 between the switch handle and the multiple fuse element whereby the former may be manipulated to effect fuse renewal movement of the latter when moved from off to on position.

5. In combination, a switch having an accessible 70 handle movable to and from on and off positions in opposite directions, and a renewable multiple fuse element normally out of operative connection with the switch handle, and means optionally manipulable for connecting the switch 75

handle to the element whereby movement of the handle will cause movement of the element for fuse renewal.

6. A multiple fuse device comprising a body closed by a movable cover which mounts therein an externally handled switch and a movably and removably mounted multiple fuse element, and means connecting the switch handle to the multiple fuse element whereby the former may be manipulated to effect fuse renewal, the cover being movable to expose said fuse element for replacement.

7. A multiple fuse device comprising a body closed by a movable cover which mounts therein an externally handled switch and a movably and removably mounted multiple fuse element, and means connecting the switch handle to the multiple fuse element whereby the former may be manipulated to effect fuse renewal, the cover being movable to expose said fuse element for replacement but only when the switch is in off position.

8. A multiple fuse device comprising a body containing a removable multiple fuse element and closed by a movable cover which may be opened to expose the element for replacement, and a switch normally operable independently of the element for controlling the circuit line through the element, the cover and the switch having an interlocked arrangement whereby the cover may not be opened when the switch is closed and the switch may not be closed when the cover is open, and whereby the switch may be manipulated when the cover is closed, and when an option-

ally operable connection is created between the switch and the element to effect fuse renewal movement of the element.

9. A multiple fuse device comprising a body containing a removable multiple fuse element and closed by a movable cover which may be opened to expose the element for replacement, and a switch normally operable independently of the element for controlling the circuit line through the element, the cover and the switch having an interlocked arrangement whereby the cover may not be opened when the switch is closed and the switch may not be closed when the cover is open, and whereby the switch may be manipulated when the cover is closed and a fuse has blown, and when an optionally operable connection is created between the switch and the element, to close the circuit, if open, and simultaneously effect fuse renewal movement of the element.

10. In combination, a switch having an accessible handle movable to and from on and off positions in opposite directions, and a renewable multiple fuse element normally out of operative connection with the switch handle, and means optionally manipulable for connecting the switch handle to the element whereby movement of the handle will cause movement of the element for fuse renewal, and means for preventing movement of the element in any but a proper direction regardless of the direction of movement of the switch handle.
